L. M. RABINOWITZ

ATTACHMENT FOR SEWING MACHINES

Filed April 22, 1924

INVENTOR
LOUIS M. RABINOVITZ
BY
Charles J. Wilson
ATTORNEY

UNITED STATES PATENT OFFICE.

LOUIS M. RABINOWITZ, OF NEW YORK, N. Y.

ATTACHMENT FOR SEWING MACHINES.

Application filed April 22, 1924. Serial No. 708,136.

This invention relates to an attachment for sewing machines, and one of the objects thereof is to provide a new and improved device for attaching a strip of fabric, having 5 hooks or eyes mounted thereon, to a garment or to another piece of fabric.

Another object of the invention is to provide a device of the above character, which while joining the hook or eye carrying strip 10 of the garment or other piece of fabric, will bind the free or raw edge of the material of said last element, adjacent its point of joinder with the hook or eye carrying strip.

Another object of the invention is to provide a new and improved device for simultaneously positioning and stitching together, and binding one of the edges of a hook and eye carrying strip and a garment or other piece of fabric.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawing wherein I 30 have shown a preferred form of embodiment of my invention;

Figure 1 is a top plan view of my improved device, showing the material to be operated upon in position therein.

Figure 2 is an end elevation thereof.

Figure 3 is a horizontal sectional view taken on the line 3—3 of Fig. 1, looking in the direction of the arrow.

Figure 4 is a top plan view of my improved device, parts being broken away better to illustrate certain details of construction; and

Figure 5 is a view taken substantially on line 5—5 of Fig. 4, looking in the direction of the arrow.

Figure 6 is a section of the fabric near the edge upon an enlarged scale.

Referring now to the drawing, wherein similar reference characters refer to similar parts throughout the views thereof, the reference numeral 1 denotes a portion of the table or platen of a sewing machine, having the usual apertures or slots 2, through which the fabric feeding devices are projected to en-

gage and feed the fabric. The aperture 55 through which the needle works is indicated at 3.

If desired, the table 1 may be a separate attachment, and be secured to the table proper of the sewing machine by means extending 60 through the aperture 4.

Pivottally and adjustably mounted upon the table 1, is a plate 5, the securing and adjusting means comprising a screw 6, threaded into the table 1, which extends through a 65 slot in the plate 5. This plate, when the device is in operation, is immovably secured to the table 1, if a proper adjustment has been effected.

Pivottally mounted to the plate 5 by means 70 of the screw 7 is a bracket plate 8, which is adapted to lie closely adjacent the plate 5, so that it can be swung into the position shown in full lines of Fig. 1, or to the position shown in the dotted lines in said figure. The 75 full lines show the normal or working positions of the parts.

Threaded through an upstanding flange 9 formed in the plate 5, is a stop or abutment screw 10, the edge of which is adapted to engage with the edge 11 of plate 8, whereby the normal position of plate 8 may be adjustably determined. A leaf-spring 12 fastened to the bracket plate 8 by the screws 13, is provided with a flange end 14, which engages the flange 80 85 9 to hold said bracket plate in its normal or working position.

It will be seen that when the bracket plate 8 is swung outwardly to the position shown in the dotted lines of Fig. 1, the flanged end 90 14 of the leaf-spring 12 will ride over the flange 9 and permit the outward swinging of the bracket plate, and that when the latter is swung to its normal position, the flange 14 of said leaf-spring will again ride over the flange 9 of the plate 5, whereupon the parts 95 will thereafter be maintained in their normal positions.

Adjustably mounted upon the forward edge of the bracket plate 8, as by means of the screws 15, is a binding folder 16. This binding folder is of a known construction, and therefore it is not necessary to illustrate it or describe the structural details thereof in this specification. This device operates upon a strip of binding fabric, such for instance as is shown at 17, and folds it upon itself along a median line, and then turns each of the free

edges of said strip inwardly and rearwardly upon itself, as indicated at 18 in Figure 3.

Carried upon the folding device 16 is a platform 19, which when the parts are in normal positions, overlies the forward edge of the table 1, and is spaced vertically therefrom.

Mounted in a groove or recess 20 formed in the upper forward face of the table 1, is a guide 21, which guide is formed of a strip of metal, the edges of which are bent upwardly and inwardly to provide the passageway 22. The free edges 23 and 24 of this guide member terminate short of each other to provide the slot 25.

15 The guide 21 is adapted to receive a strip of fabric upon which has been mounted preferably by the rivets 26 a plurality of hooks or eyes 27, and the slot 25 is so disposed, and is of a sufficient width, to receive the rivets 26, the edges 23 and 24 of said slot serving to guide the fabric strip, indicated at 28, through the engagement of the rivets with said guide member.

Thus it will be seen that strips similar to 28, of different widths, may be passed through the guide 21, inasmuch as the guiding is done by the engagement of the rivets of the hooks or eyes with the edges 23 and 24 of the slot 25. The slot 20 of the table 1 is provided with 30 an incline 29, which rises rearwardly to a level with the face of the table 1.

Referring now to Figures 1 and 2 of the drawings, it will be seen that the inner end 30 of the folder 16, when the parts are in 35 normal position, is disposed directly above the hooks or eyes carried upon the strip 28, providing a U-shaped space in the folded binding strip 17, through which may be passed the edge 31 of the garment 32, or other 40 piece of material, which is to be attached to the hook or eye carrying strip.

The garment or other piece of fabric 32, passes over the platform 19, so that the edge thereof is received in the folded portion of 45 the binding material, and the parts are so disposed relative to the needle, that the needle, when in operation, will pass through the inwardly turned edges of the binding material, the edge of the garment or other piece 50 of fabric 32, and the hook or eye carrying strip 28, whereby the edge 31 of the garment 32 will be bound while being stitched to the hook or eye carrying strip 28.

In practice the parts are so related that the 55 line of stitching, indicated at 33, will pass through the layers of fabric directly behind the point of fastening of the hooks or eyes 27 to the strip 28, so that the bound edge 31 of the garment or strip 32, will partly overlie the 60 hooks or eyes.

Mounted upon the table or plate 1 is a guide member 34, the latter comprising a screw, the shank 35 of which is threaded into an aperture formed in the table. This screw is provided with a pair of circular shoulders 36

and 37, of different diameters, the shoulder 37 being located directly beneath the shoulder 36. The object of this construction is to provide for the guide engaging hook or eye carrying strips of different widths. This can 70 be accomplished by raising or lowering the screw guide to dispose either of the shoulders to the edge of the strip 28. This guide member is located directly opposite the point where the needle enters the superimposed 75 fabrics, and is adapted to engage with the edge of the hook or eye carrying strip 28. Thus it will be seen that this strip 28 is guided to travel in a straight direction, both in front and behind stitching means comprising the 80 needle, which is indicated at 38.

Having thus described the construction of this embodiment of my invention, the operation thereof which should be largely understood, is as follows:

The parts being positioned as shown in Figs. 1 and 2, the strip of binding is fed into the folder 16, as illustrated in said figures, and a hook or eye carrying strip, such as shown at 28, is fed to the guide 21. These strips are thereafter then automatically fed to their respective folding or guiding devices by the feed mechanism of the sewing machine.

90 The operator then passes the edge of the garment or strip of fabric 32 over the platform 19, so that the edge thereof passes through the fold, indicated at 39 of the binding, whereupon the parts are fastened together by the operation of the needle to form 100 the line of stitching 33.

As has already been explained, the hook or eye carrying strip 28 is positively guided at both sides of the stitching means, and the inner end 30 of the binder 16 is disposed to discharge the folded binding material directly above the fastening devices of the hooks or eyes. Therefore, it will be seen that once the strips of fabric are caught by the stitching means, it is merely necessary for the operator 110 to maintain the edge of the garment, or other piece of fabric, in engagement with the fold 30 to insure that the parts will be in their proper superimposed relation when they 115 reach the stitching means.

It will accordingly be seen that I have provided a construction well adapted to attain, among others, all the aims and objects above pointed out, in a simple and facile manner, and I have provided a device which will perform its functions with exactness and precision, while at the same time effecting a considerable saving of labor.

120 As many changes could be made in this construction without departing from the scope of the following claims, it is intended that all matter contained in the above description or shown in the accompanying drawing shall be interpreted as illustrative 125 only and not in a limiting sense.

Having thus described my invention what I claim as new and desire to secure by Letters Patent is:

1. In a device of the class described, the combination with stitching means, of a table or platen adapted to support the work, a guide member carried by said table, said guide member being provided with a slot, and said guide member being adapted to receive a strip of hook or eye bearing fabric, with said hooks or eyes projecting through said slot, a plate pivotally mounted upon said table, a binding folder mounted upon said plate, and a platform mounted upon said folder.
2. In a device of the class described, in combination with stitching means, a table or platen through which the stitching means operates, a channeled guide member mounted upon said table adapted to receive a strip of fabric provided with hooks or eyes, said guide member being provided with a longitudinally extending slot through which said hooks or eyes extend, the edges of said slot, through their engagement with said hooks or eyes, providing guiding means for said strip forwardly of the stitching means, means carried by said table rearwardly of the stitching means, adapted to engage the edge of said hook or eye bearing strip, means for delivering a folded strip of binding material in parallel relation to said first named strip, the fold of said binding material being adapted to receive the edge of a garment or other strip of material, whereby said first named strip, said binding material, and the edge of said garment or other piece of material, are delivered in superimposed relation to be acted upon by said stitching means.
3. In a device of the class described, in combination, a table or platen adapted to support the work, a slotted guide member secured to said table, a plate adjustably mounted upon said table, a bracket plate pivotally mounted upon said last named plate, a binding folder carried by said bracket plate, said binding folder and said slotted guide member being arranged at right angles to each other and a platform carried by said folder, and disposed above said slotted guide member, and in spaced relation with respect thereto.
4. In a device of the class described, in combination with stitching means, a table or platform adapted to support the work, and through which said stitching means operates, a guide member carried by said table and

disposed in parallel relation with the line of stitching produced by said stitching means, said guide member being provided with a guide slot, a binding folder having its delivery end disposed about said guide slot, said binding folder and said guide member being arranged at right angles to each other and a platform carried by said binding folder.

5. In a device of the class described, in combination with stitching means, of a table or platform adapted to support the work, and through which said stitching means operates, a slotted guide member adapted to receive a strip of hook or eye bearing fabric, the slot of which engages the fastening means of said hooks or eyes, whereby said strip is guided to the stitching means, an adjustable guide member carried by said table behind said stitching means and adapted to engage said strip, a binding folder member adjustably mounted upon said table, and adapted to guide a strip of binding material in superimposed relation to said first named strip, and a platform carried by said folder over which the edge of a garment or other piece of fabric may be passed, so that the edge thereof is received in the fold of said binding material, and be led and guided thereby to said stitching means, whereby said binding, the edge of the garment, or other piece of fabric, and said hook or eye bearing strip may be simultaneously operated upon by said stitching means.

6. In a device of the class described, in combination, with stitching means for uniting a garment or other piece of fabric, a strip of hook and eye bearing fabric and a strip of binding material, of means for simultaneously binding the edge of the garment or other piece of fabric, and stitching it to said hook or eye bearing strip.

7. In a device of the class described, the combination with a stitching means, for uniting a garment or the like, a strip of hook or eye bearing fabric and a binding strip, a table or platen for supporting the work and through which said stitching means operates, and means for guiding the edge of said garment, said strip of hook or eye bearing fabric, and said binding strip past said stitching means, whereby the edge of said garment, said binding strip, and said hook or eye bearing strip will be fastened together by said stitching means in a single operation.

In testimony whereof I affix my signature.

LOUIS M. RABINOWITZ.
